UNITED STATES PATENT OFFICE.

JOHN H. AKIN AND CHARLES C. ANDERSON, OF CRESTON, IOWA.

METAL RAILWAY-TIE.

No. 874,556.

Specification of Letters Patent.

Patented Dec. 24, 1907.

Application filed April 30, 1907. Serial No. 371,133.

To all whom it may concern:

Be it known that we, JOHN H. AKIN and CHARLES C. ANDERSON, citizens of the United States, residing at Creston, in the county of Union and State of Iowa, have invented certain new and useful Improvements in Metal Railway-Ties; and we do hereby declare the following to be a full, clear, and exact description of the invention, such as will enable others skilled in the art to which it appertains to make and use the same.

Our invention relates to new and useful improvements in metallic rail ties and our object is to provide means for securely clamping the rails upon the ties.

A further object is to provide means to hold the rails a predetermined distance apart.

A still further object is to provide a brace member between the ties for supporting the rails.

Other objects and advantages will be hereinafter referred to and more particularly pointed out in the claims.

In the accompanying drawings which are a part of this application Figure 1 is a perspective view of a section of railway track showing a pair of our improved ties in use. Fig. 2 is a transverse sectional view through the track way. Fig. 3 is a top plan view of one of the ties applied to use, and Fig. 4 is a detail perspective view of a locking bar employed for securing the parts of the tie together.

Referring to the drawings in which similar reference numerals designate corresponding parts throughout the several views 1 and 2 indicate the usual form of rails employed in connection with railway tracks and 3 indicates our improved form of metallic tie, each of said ties preferably consisting of two sections 4 and 5 and the sections are preferably formed of angle iron and when so constructed one wing of each of the angle irons is disposed in a horizontal position while the opposite wing thereof is in a vertical position so that the two vertical portions will abut against each other.

Each of the vertical portions of the sections 4 and 5 is provided with a pair of notches 6 and 7 respectively which are located at the proper distance from each end of the tie to receive the rails 1 and 2, and each of the notches is provided with overhanging lips 8 and 9 respectively, which are

adapted to extend over and engage the base 10 of the rails, the lower faces of said lips being tapered to fit the contour of the base of the rails.

The notches in the sections 4 are staggered 60 with relation to the notches in the section 5 so that when the two sections, forming the tie, are placed in position on the rails, the lips at one end of the notches 6 will engage that portion of the base at the right of the 65 body of the rails, while the lips 9 at the opposite ends of the notches 7 will engage that portion of the base at the left of the body of the rail, or if desired each alternate tie may be reversed in this respect.

When the sections of the tie are arranged in the manner just described the right hand end of the section 4 will extend beyond the corresponding end of the section 5 while the left hand end of the section 5 will be an equal 70 distance beyond the corresponding end of the section 4; and in order to hold the sections of the tie in engagement with the base of the rails and direct pressure thereon, we provide registering channels 11 and 12, in 75 the meeting faces of the vertical portions of the tie, through which is extended a locking bar 13, one end of which is provided with an angular extension 14, while the opposite end thereof is provided with threads 15 on which 80 85 is adapted to take a binding nut 16.

When the locking bar is placed in position, the extension 14 engages the protruding end of the section 5 while the binding nut engages the protruding end of the section 4, so that 90 when the nut is turned home on the threaded end of the locking bar, the lips 8 will be moved into engagement with one edge of the base of the rail, while the lips 9 will be drawn into close relation with the opposite side of 95 the base of the rail, thereby positively locking the rails to the tie, and at the same time spacing them a predetermined distance apart.

In order to more securely lock the sections of the tie together and relieve the locking bar 100 from undue strain, we provide locking bolts 17, which extend through slots 18 in the vertical portions of the sections 4 and 5 so that when the tie has been properly located below the rails the locking bolts are placed in position through the slots and the nuts 19 thereon tightened, thereby relieving a portion of the strain from the locking bar.

In order to support the rails between the ties so that said ties can be spaced a consid- 110

erable distance apart, we provide supporting beams 20 which extend length wise of the rail and have their ends resting upon the horizontal wings of the sections 4 and 5, said 5 supporting beams consisting of parallel vertical walls 21, which are connected together adjacent their upper ends by means of a horizontally disposed wall 22, said wall 22 being slightly below the upper ends of the walls 21 10 to form a cavity 23 in which the base of the rails is seated, the projecting portions of the walls 21 engaging the opposite edges of the base and thereby holding the supporting beams in position below the rails. It will 15 thus be seen that the ties can be spaced a considerable distance apart and the beams employed for supporting the rails instead of employing an additional number of ties, and it will also be seen that the rails will be positively held against spreading, or in fact any movement after the sections of the ties are 20 properly secured thereto.

It will further be seen that the parts of the tie can be quickly placed in position below 25 the rails and the sections thereof firmly locked together.

1. The combination with railway rails, of a supporting tie, said tie consisting of angular sections said sections having notches therein, 30 lips at each end of said notches and means to direct said lips into engagement with the rail.

2. A tie of the class described comprising angular sections, the vertical portion of said sections having notches in the upper 35 edges thereof to receive rails, lips at each end of said notches adapted to be directed into engagement with the base of the rails, a locking bar between the meeting faces of said sections adapted to move said sections longitudinally in opposite directions and the lips 40 into engagement with the rails.

3. The herein described rail tie comprising sections, portions of said sections being horizontal and portions thereof vertical, the vertical sections having a pair of 45 notches in the upper edge thereof, lips at the end of said notches and means to move said sections longitudinally in opposite directions

to engage the lips with rails placed in said notches. 50

4. The herein described rail tie comprising a pair of angular sections the meeting faces of which are provided with registering channels, notches in said sections, lips at the ends of said notches adapted to 55 extend over and engage the base of rails placed in said notches, a locking bar seated in said channels one end of which is adapted to engage one end of one of the sections and means at the opposite end thereof to 60 engage the end of the opposite section, whereby said sections may be moved longitudinally in opposite directions.

5. The herein described rail tie comprising a pair of angular sections the meeting faces of which are provided with registering channels, notches in said sections adapted to receive rails, lips at the ends of said notches, a locking bar seated in said channels an angular extension at one end 65 of said bar adapted to engage the end of one section, a binding nut for the opposite end of said bar adapted to engage the opposite end of the other section whereby when the nut is directed on to said bar, 70 the sections will be moved longitudinally and in opposite directions, and a portion of said lips into engagement with said rails and means to lock said sections in their adjusted position. 75

6. The combination with a railway rail of means to support the same comprising ties formed of angular sections, means to secure the ties to the rails, and supporting beams adapted to rest on the horizontal portions of the tie, and having a cavity in their upper faces to receive the base of the rail. 80 85

In testimony whereof we have signed our names to this specification in the presence of two subscribing witnesses.

JOHN H. AKIN.

CHARLES C. ANDERSON.
